UNITED STATES PATENT OFFICE.

SIDNEY M. ISRAEL, OF RICHMOND HILL, NEW YORK.

DESIGN FOR A BOTTOM PLATE FOR ELECTRIC-LIGHT FIXTURES.

Application filed October 6, 1921. Serial No. 505,947. Term of patent 3½ years.

To all whom it may concern:

Be it known that I, SIDNEY M. ISRAEL, a citizen of the United States, residing at Richmond Hill, county of Queens, and State of New York, have invented a new, original, and ornamental Design for Bottom Plates for Electric-Light Fixtures, of which the following is a specification, reference being had to the accompanying drawing, forming part thereof.

Fig. 1, is a top or inner side view;
Fig. 2 is a side elevation; and

Fig. 3, is a view of the face or under side of a bottom plate for electric light fixtures, showing my new design.

I claim:—

The ornamental design for a bottom plate for electric light fixtures, as shown.

SIDNEY M. ISRAEL.
